Inventor:

Millard F. Jenning

UNITED STATES PATENT OFFICE.

MILLARD F. HENNING, OF OAKLAND, CALIFORNIA.

WINDOW SCREEN.

Application filed February 4, 1924. Serial No. 690,676.

To all whom it may concern:

Be it known that I, MILLARD F. HENNING, a citizen of the United States, residing at Oakland, in the county of Alameda and 5 State of California, have invented a new and useful Improvement for Window Screens, of which the following is a specification.

The invention relates to window screens, and more particularly to means whereby ordinary screens may be applied to and removed from windows.

An object of the invention is to provide new and improved fastening means for removably securing a window screen to a window sash.

Another object is to provide improved means for adjustably securing a screen to a window sash in such relation as to provide any desired degree of raising or lowering 15 of the window sash.

Another object is to provide screen fastening devices that consist of a minimum of parts and which can be produced at a low cost.

Another object is to provide screen holders which constitute a guide for raising or lowering sashes and also to maintain the screen in proper position.

With these and other objects in view the invention consists in providing guide strips secured at one end to the window sashes and provided with guideways and portions extending over the screen and holding the screen against the sashes or in the window frame to guard the desired opening.

The invention consists further in certain novel features of construction, arrangement and combination of parts as will be herein-after set forth and claimed, reference being had to the accompanying drawing in which,

Figure 1 is an elevation of a window frame and its sashes, showing the invention as applied,

Figure 2 is a side elevational section,

Figure 3 is a perspective view of the screen holder before attachment for use.

In the drawing 5 indicates an ordinary window frame in which are mounted as usual the sashes S.

The screen is indicated by the reference numeral 6 and comprises the conventional wire fabric and top, bottom and side rails 7 and 8 respectively.

The holders and fasteners comprise a pair of elongated flat plates or bars 9 offset adjacent one end 10 to provide the shoulder 11.

The comparatively short end portion 10 is provided with a key hole slot 12 the purpose of which will later appear.

The elongated offset portion 9 is provided 60 with an elongated narrow slot 13 which extends from the free end to adjacent the shoulder 11.

In applying the invention, it may be done in several ways, but I will now set forth one 65 practical method: The screen is put in place in the frame against the window sash, headed screws 14 are then placed in the side rails of the sash at such points as desired, and the keyhole slot 12 of the bars 9 passing 70 over the heads of the screws the bars drop down with the straight part of the keyhole 75 12 embracing the shank of the screw and behind the head thereof the slotted portion of the bars lying against the screen frame; the screws 14 are now tightened up securely holding the bars in place. Screws 15 are now inserted through the slots and driven into the side rails of the sashes.

The device is now installed for use and the 80 screen can slide up and down with relation to the sashes, removed entirely therefrom or the sashes slid in relation to the screen; this latter operation is made possible by fastening the screens at either the top or bottom 85 of window frame, such as by hooks and screw eyes 16 or other suitable coacting latching means.

The various parts of the device can be 90 separated and stored, or packed in small compass for transportation, or the screen when once applied may be left on the sash, and adjusted to any position within the limits of its size and the length of the slot.

From the foregoing it is apparent that I 95 produce an extremely simple, efficient and cheap device well adapted for objects in view, it being understood that such changes may be made as will fall within the scope of the appended claims.

Having thus fully described my invention and its application, what I claim is:

1. The combination with a window frame, window sashes and a screen, of screen holders comprising a pair of elongated plates offset at one end and detachably secured at such end to the window sashes, cooperating means carried by said plates and the screen for slidably maintaining the screen relatively to the sash, and cooperating latch 110 means carried by an end rail of the screen and the window frame whereby the sashes

may be raised or lowered to provide openings to be guarded by the screen.

2. The combination with a window frame, window sashes and a window screen, of a pair of slotted screen holding plates, said plates offset and detachably secured at one end to the side rails of the window sash, guide and binding pins secured to said screen and projecting through the slots of the plates, and coacting latch means carried by the end rail of the screen and the window frame.

3. The combination with a window frame,

window sash and a window screen of a pair of vertical bars having one end offset inwardly and provided with a keyhole slot in said offset portion, whereby to be removably attached to the side rails of the sash, said bars having elongated vertical slots therethrough, headed screws mounted on the sash and adapted to cooperate with said keyhole slots, and headed screws mounted on the side rails of the sash and extending through said elongated slots.

MILLARD F. HENNING.
